UNITED STATES PATENT OFFICE.

NAZAIRE LACROTTÉ, OF PARIS, FRANCE.

PROTECTING MASK FOR BOXING PUPILS.

Application filed February 4, 1921. Serial No. 442,422.

To all whom it may concern:

Be it known that I, NAZAIRE LACROTTÉ, engineer, citizen of the Republic of France, residing in Paris, France (and whose post office address is 136 Avenue Parmegtier), have invented certain new and useful Improvements in Protecting Masks for Boxing Pupils; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

This invention relates to a protecting mask with elastic padding constituted by hollow rubber members or pouches, and adapted to be secured to the face whereby 20 the wearer is enabled to carry out boxing exercises without receiving any injury whatever from the strokes, these latter being deadened by the effect of the said padding. The mask according to my invention, which may 25 be used to protect the entire face or only a portion thereof, is essentially composed of sheets of felt and a sheet of leather having secured thereto at the proper places hollow rubber members or pouches which are in 30 turn covered by a leather sheet. The whole is enclosed within an internal envelope of cloth fabric and an external envelope of thin leather or like flexible material, and the entire device is secured to the face by suitable 35 means.

As shown in the accompanying drawings, Fig. 1 is a perspective view of a mask constructed according to my invention. Fig. 2 is a front view of the same, and Fig. 3 a 40 vertical section on the axis thereof. Fig. 4 is a partial section showing one of the means which may be employed for holding the said hollow pouches in place. Fig. 5 is a perspective view of a modified form of construction 45 of the mask, and Fig. 6 a sectional view of a hollow pouch with the enclosing padding for the same. Fig. 7 shows a mask comprising only the ear protecting portions.

In the device according to Figs. 1 to 6, the 50 mask comprises two flexible side members 1, 1 for protecting cheeks, nose and ears, a central cut out portion 2 to contain the nose, an elongated aperture 3 for respiration through the mouth; a projecting portion 4 for protecting the lower lip; and a curved portion 5 covering the chin. The whole de-

vice is constituted by a foundation or backing sheet constructed of sufficiently thick felt and having secured thereto the hollow rubber pouches which are air inflated and 60 disposed at suitable points for effectually protecting the boxer's face. Two of the said pouches are disposed at 7 at each end of the side members 1, 1 and another 8, at the middle part of the said members. 65

The central cut out portion 2 may be strengthened internally by a metal stiffening member 9 which affords a good protection for the sides of the nose and the upper lip, in combination with the punches 10 disposed 70 at the sides of the said cut out portion. Below the elongated aperture 3 is disposed another pouch 11 for protecting the lower lip. The mask is also provided at the lower middle part thereof with an inwardly projecting 75 portion 5 having disposed therein the three pouches 12. These various pouches are secured to their backing by any suitable means, but can be advantageously held in place by two overlapping strips 13 which are 80 sewed at 14 to the felt 6 or to the leather which may be disposed upon the latter. The entire mask is faced with a textile fabric or like flexible material 15. The mask is held upon the boxer's face by an elastic band 16 85 bearing upon the forehead and another band 17 also of an elastic character fitting over the top of the head, in combination with a strap 18 made in two parts and provided with a tongueless buckle and designed to be 90 tightened at the back of the head.

In the arrangement shown in Figs. 5 and 6, the mask comprises an upper portion for the forehead, 19, which is suitably padded and contains two rubber pouches 20. This 95 forehead portion is connected to the upper parts of two flaps 21, 21 protecting the ears, which are likewise padded and each provided with a rubber pouch 22 at the central part thereof. The lower part of each of the flaps 100 21 is secured to a forwardly projecting portion 23 for protecting the upper jaw and the nose against the blows. The padding of each of the portions 23 contains a rubber pouch 24. 105

The space formed between the two portions 23 serves to contain the nose, and the two edges of the said portions are connected by a forwardly situated strip of textile fabric 26 which is secured to the forehead 110 portion 19 by a narrow strip of fabric 25. The lower part of the said nose aperture is

provided with a narrow strip of textile fabric 26^a which is placed over the upper lip.

This mask is fitted upon the face by means of a set of elastic bands 27 bearing upon the top of the head and having secured thereto another band 28 fitting over the back of the head, in combination with the strips 29 secured to the bottom of the flaps 21 and adapted to be tied under the chin.

10. The above described mask may as shown in Fig. 5 comprise an arched member 30 protecting the top of the head, as well as a lower member 31 for protecting the chin. The members 30 and 31 may be provided to this effect with one or two rubber pouches 30^a, 31^a respectively as indicated in dotted lines.

15. The padding of the mask may be constructed advantageously as shown in Fig. 6. A felt member 6 disposed adjacent the inside of the mask has sewed thereto a leather sheet 32 to which is secured the rubber pouch by means of overlapping bands 13 as in the arrangement Fig. 4, and the said pouch is 20 surrounded by felt bands 33 covered by a leather sheet 34 which is in contact with the outer side of the pouch. This assemblage of leather and felt sheets is held together by stitching, and the whole is enclosed within 25 an inner envelope of textile fabric 35 and an outer envelope of thin leather 36.

30. The mask may be constructed in a simpler form as shown in a rear perspective view Fig. 7 and in this case it comprises only two 35 padded portions 21^a for protecting the ears, which are each provided with a rubber pouch 21^b as indicated in dotted lines and are cross connected at the top by a set of elastic bands 27 secured to another elastic 40 band 25 fitting upon the back of the head. At the front part the two padded portions 21^a are connected by an elastic band 37 bearing upon the forehead, and they are connected at the bottom by an elastic band 38 45 fitting under the chin.

Having now particularly described, and ascertained the nature of my said invention and in what manner the same is to be performed, I declare that what I claim is:

50. 1. A protecting mask for boxing pupils, comprising two padded portions of oval shape for protecting the ears, each comprising a leather sheet covered with a plurality

of layers of felt, a hollow rubber pouch disposed upon the said leather sheet, a leather sheet covering both the said felt portion and the said pouch, and an envelope enclosing the entire device; a set of elastic bands fitting upon the top of the head; an elastic band applied against the forehead and another elastic band fitting under the chin. 55

2. A protecting mask for boxing pupils, comprising two padded portions of oval shape for protecting the ears, constituted by a plurality of layers of felt and leather; a hollow rubber pouch disposed within each of the two padded portions, an upper padded portion for protecting the forehead and connecting the two padded ear-protecting portions, two hollow rubber pouches disposed within the forehead-protecting padding, two padded portions extending from the bottom part of the said oval-shaped padding and adapted to protect the upper jaw and the nose; a hollow rubber pouch disposed within each of the said extensions; a band of textile fabric connecting these two extensions; another band of textile fabric connecting the said lower extensions to the forehead padding; a set of elastic bands fitting upon the top of the head, and two bands adapted to be tied under the chin. 70 75

3. A protecting mask for boxing pupils, comprising two padded portions for protecting the ears; a hollow rubber pouch disposed within each of the said padded portions; an upper padded portion for protecting the forehead; two hollow rubber pouches disposed within the said padded portion; two lower padded extensions for protecting the upper jaw and the nose; a hollow rubber pouch disposed within each of the said extensions; a band of textile fabric connecting these two extensions; another band of textile fabric connecting the said lower extensions to the forehead padding; an upper padded portion for protecting the top of the head; hollow rubber pouches disposed within the said padded portion; a lower padded portion for protecting the chin; rubber pouches disposed within the said padded portion; and an elastic band fitting around the back 90 95 95 of the head.

In testimony that I claim the foregoing as my invention, I have signed my name.

NAZAIRO LACROIX.
